(57) **CLAIM**

The ornamental design for handle for cookware, as shown and described.

DESCRIPTION

FIG. 1 is a perspective view of a “handle for cookware” showing my new design;

FIG. 2 is a front elevational view of FIG. 1;
FIG. 3 is a side elevational view of FIG. 1;
FIG. 4 is a top plan view of FIG. 1; and,
FIG. 5 is a bottom plan view of FIG. 1.

The broken line showings in FIGS. 1-5 represent the environment in which the design resides and forms no part of the claimed design.
